PROCESS FOR PREPARING A LIQUID OXYGEN EXPLOSIVE

Samuel W. Martin, Oak Park, Ill., assignor to Great Lakes Carbon Corporation, New York, N. Y., a corporation of Delaware

No Drawing. Application August 12, 1955,
Serial No. 528,120

3 Claims. (Cl. 52—1)

This invention relates to a process for preparing liquid oxygen explosives. More particularly, this invention relates to a process for preparing liquid oxygen explosives in which a specially prepared absorbent carbon is employed.

Mixtures of highly volatile oxidizing agents such as liquid oxygen, liquid air or liquid ozone with a combustible substance, such as finely divided carbon, have previously been proposed as explosives. This type of explosive is ordinarily employed by forming cartridges of the finely divided carbon, soaking the cartridges in liquid oxygen or other volatile oxidizing agents and then within a short time using the saturated cartridges in blasting operations. This kind of explosive is not only powerful but has certain advantages over other types of explosives. Since the components of these explosives are mixed at the site where they are to be used and since these components are not alone likely to explode, all hazards resulting from the transportation of an explosive mixture are avoided. Also, if the prepared charge fails to detonate for any reason the charge is rendered harmless by the subsequent evaporation of the volatile oxidizing agent. However, the employment of explosives of this type in the past has been dangerous due to the fact that the mixture of carbon and liquid oxygen, in most cases, is easily detonated by impact or friction. Accordingly, there is a great danger of premature explosions caused by rocks or other objects falling on the explosive mixture while it is being lowered into drill holes or by other shocks accidentally transmitted to the mixture.

Attempts have been made to desensitize liquid oxygen explosives by diluting the absorbent carbon with inert absorbents. For the same reason attempts have been made to "fire proof" the absorbent carbon by coating or impregnating with various chemicals. These attempts to desensitize or fire proof the carbon have not only been costly but also have not been entirely effective.

It is therefore an object of this invention to provide a process for producing an explosive of the liquid oxygen type which without the addition of desensitizing or fire-proofing agents, is less sensitive to detonation by impact or friction than any previously known liquid oxygen explosives.

It is a further object of this invention to provide a process for producing a liquid oxygen explosive, which despite the fact that it is relatively safe to handle, is nevertheless effective, when properly detonated, with respect to its disruptive or shattering properties.

It is a further object of this invention to provide a process for producing a liquid oxygen explosive, in which a hard, granular carbon is prepared which is sufficiently absorbent with respect to liquid oxygen or similar volatile oxidizing agents to function safely and effectively in said explosive.

The above objects as well as others which will become apparent upon understanding of the invention as herein described, are accomplished by the flash oxidation-calcination of finely divided swelling bituminous coals at a temperature above 800° C. and then causing liquid oxygen or other equivalent volatile oxidizing agent to be absorbed by the resulting hard, granular absorbent carbon product. The method of oxidizing and calcining the coal particles will be described herein and is so conducted that

2

the resulting absorbent carbon product will have a bulk density of 10-20 lbs. per cu. ft.; a volatile content of no more than 5% by weight; ash content of about 8% to about 15% by weight; and particle size of at least 70% less than 200 mesh.

The term "flash oxidation-calcination" as used herein and in the appended claims may be defined as a method whereby finely divided particles of swelling bituminous coal are subjected to a very rapid upheat rate, estimated to be in excess of 1000° C. (particle surface temperature) per second, into the temperature range of about 800° C. or higher. This rapid upheat of the coal particles is conducted in the presence of air or other oxygen-containing or oxidizing gas, which serves not only to burn the volatile matter evolved from the coal thereby making the process self-sustaining but also serves to oxidize a portion of the fixed carbon of the resulting charred particles to provide the proper structure which renders the final product suitable for absorption of liquid oxygen. The term "flash oxidation-calcination" further connotes the necessity for heating the coal particles at a sufficiently rapid rate so as to initially expand the individual particles even though they may be subsequently reduced in overall size by oxidation. The bulk density of the final product must be maintained at a value of 10-20 lbs./cu. ft. If the coal particles are heated at a sufficiently rapid rate into a temperature range of 800° C. or higher, the particles become plastic and swell due to devolatilization; this type of operation is essential for satisfactory production of the absorbent carbon under consideration.

The step of expansion and oxidation is best performed by feeding a crushed and sized swelling bituminous coal into a rapidly moving stream of oxidizing gas at a temperature above about 800° C. (reactor temperature). This results in an initial expansion and devolatilization of the coal particles together with the burning of the volatile matter and a portion of the fixed carbon in the coal. The oxidation and heating are controlled so that the resulting product has an ash content of about 8% to about 15% by weight (depending in part on the ash content of the coal); the particles of the product will have a size within a range of at least 70% less than 200 mesh. The flash oxidation-calcination operation must also be conducted so as to produce particles having 5% or less by weight of volatiles.

While it is preferable that the source of heat used in each of the stages be the particle itself, it is conceivable and within the contemplation of this invention that a substantial portion of the heat may be supplied by some outside source or auxiliary fuel. The most rapid upheat rates are, of course, obtained using the particle itself as the source of heat.

The types of coal which are suitable for the manufacture of the absorbent carbon which is employed in the practice of the present invention are broadly classified as "swelling bituminous coals." These coals fall within the types of coal set out in the *Encyclopedia Britannica*, vol. 5, page 872 (1948):

60	Type of Coal	Percent V. M.	Percent C	Percent H
Semi-bituminous (semi-coking)	12-15	80-90	4.5-5	
Bituminous (coking)	12-26	75-90	4.5-5.5	
Bituminous (low fixed C)—coking	<35	70-80	4.5-6	
Gas coal	28-40			

65 Any swelling bituminous coal having a volatile matter content in excess of about 12% by weight will be suitable for the preparation of the absorbent carbon employed in the present invention. These types of coal are characterized by softening when heated through the plastic state and will swell if the volatile matter of each particle is driven off at a sufficiently high rate.

The aforesaid bituminous coal employed in preparing the absorbent carbon should not have too high an ash content since mineral impurities in too great an amount may result in a carbon of unfavorable detonating characteristics. In general, it may be stated that no coal should be used which will result in an absorbent carbon product having an ash content of more than 15% by weight.

In preparing the bituminous coal described above for the first stage flash-calcination operation, the coal must be suitably ground or milled to produce finely divided particles. This involves the use of a Raymond ring roller mill, Babcock and Wilcox ball ring mill or other appropriate pulverizing apparatus which will reduce the coal to a particle size of about 95% — 100 mesh and preferably about 75 to 95% — 200 mesh. It has been found that the latter size of feed is to be preferred in order to produce from the coal a final absorbent carbon product which will have a particle size of at least 70% — 200 mesh. I also contemplate under certain circumstances the milling and classification (by either dry or wet methods) of the bituminous feed.

In preparing the absorbent carbon by the process described herein, I have found that particularly beneficial results are to be obtained by maintaining the moisture content of the raw material at a value of less than 5% by weight. Excess moisture in the bituminous coal fed to the unit in which the flash-calcination is conducted necessitates vaporization of the water to a temperature above 800° C., or whatever reactor temperature used, which sharply reduces the rate of temperature rise of the coal particles. Often this must be done by burning additional fuel in the unit since excess moisture in the particles reduces the temperature of the operation to a point where the desired results are not obtained.

The absorbent carbon, whose process of manufacture is described herein, should have a particle size of at least about 70% — 200 mesh. A finer particle size may be appropriate for certain blasting operations. For example, an explosive of higher brisance is obtained when the absorbent carbon is of a smaller particle size. However, when such smaller particle size is employed it may be necessary to adjust other physical characteristics of the particles to maintain a sufficiently low impact resistance for safety reasons.

Another requirement of the absorbent carbon produced in this invention is that it have a volatile content of no more than 5% by weight as determined by ASTM Procedure No. D271-48.

A further requirement of the absorbent carbon produced by the process of my invention is that it have a bulk density between 10. and 20. lbs. per cu. ft. Bulk density values are determined by permitting the product to fall freely into a graduated cylinder and measuring the loose-settled volume of a given weight of the product.

The absorbent carbon which is used in my invention has a black to grey fluffy appearance and is essentially non-activated. Under the microscope some of these particles appear to contain numerous perforations or channels in or near the surface of each particle; others appear to have a bubble-like surface structure with or without the aforementioned perforations or channels, all of which are presumably caused by devolatilization and oxidation during the flash heat treatment of the coal particles. This structure which is formed during the flash oxidation-calcination operation is considered essential to provide a carbon which when caused to absorb liquid oxygen will give an explosive of desirable characteristics.

In a preferred embodiment of the invention a quantity of Williams coal, Coking Seam No. 6 from West Kentucky, was pulverized to 84% — 200 mesh, the moisture content of the product being less than 5% by weight; a horizontal tube furnace of 30 inches inside diameter was preheated to a temperature of about 1450° C. by means of combustion of oil or gas after which the coal was blown into the furnace with sufficient quantity of air so that the

maximum furnace temperature was in the range of 1350—1650° C., and also in sufficient amount to reduce the volatile matter of the coal to 3 to 4% by weight, the original coal having a volatile content of 37.8%. The product was cooled by a water quench at the end of the furnace and was collected in a cyclone. The product had the following properties:

Bulk density	15.3 lbs./cu. ft.
Volatile content	4.2%.
Ash content	9.5%.
Particle size	75% — 200 mesh.

The hard, granular, finely divided absorbent carbon product was then packed in fireproofed cloth cartridges and saturated with liquid oxygen to produce a safe but effective explosive composition.

In a further embodiment of the invention the Williams coal mentioned above was ground to 90% — 100 mesh and was passed into the top of a vertical tubular furnace which had previously been preheated to 1100° C. The coal particles were suspended in a sufficient amount of air in order to reduce the volatile content of the coal to about 3% by weight and to burn a sufficient amount of the fixed carbon in the coal so that the final product had an ash content of about 9% by weight. As in the case of the foregoing operation the product was cooled by a water quench and collected in a cyclone. The particle size of the product was 73% — 200 mesh. The bulk density of the product was 17 lbs./cu. ft. and the volatile content was 3.2% by weight. The hard, granular, finely divided, absorbent carbon produced was then packed in fireproofed cloth cartridges and saturated with liquid oxygen to produce a safe but effective explosive composition.

In a further but less preferred embodiment of the invention, a bituminous coal having a volatile content greater than 20% by weight was fluidized in a furnace preferably preheated to a temperature of about 850° C. By regulation of the quantity and velocity of the air entering the fluidization unit the low bulk density particles which result are blown out of the top of the unit and collected in a product cyclone, for example after the product has reached a bulk density of less than 20 lbs./cu. ft. In this type of operation, a larger amount of fine particles will be found in the product due to the attrition incurred in the fluidizing unit. When the absorbent carbon produced is packed in the cloth cartridges and saturated with liquid oxygen a slightly less stable explosive with a higher brisance is produced.

The reactor temperatures set forth in the various embodiments of my invention are the apparent atmospheric temperatures, rather than particle temperatures, and are measured by means of thermocouples inserted into the interior of the reactors through ceramic sealed wells in the reactor walls.

In order to further illustrate the invention but with no intention of being limited thereby, the following examples are set forth in which various coals were preliminarily ground to suitable particle size, with controlled moisture content, after which the comminuted coal was fed to a stationary horizontal tubular furnace which had been preheated to a certain temperature at which the flash oxidation-calcination operation was to be conducted. The product was cooled by spraying or fogging with water either at the end of the reaction tube or just prior to the entry of the product into the cyclone. The absorbent carbon obtained was then saturated with liquid oxygen and detonated under controlled conditions permitting measurement of various explosive characteristics.

The following is an explanation of terms used in characterizing my explosive or the carbon used therein:

"Detonation velocity" was determined by measuring the time interval which elapsed between the breaking of two copper wires a known distance apart. This time interval was measured with a Hewlett Packard type 522 interval

timer. Wires to be broken were No. 30 copper wires threaded through a 4 ft. long cartridge, there being a distance of 3 ft. between the two wires. A piece of primacord was inserted into the end of the cartridge so that it was about 4" from the start wire. This distance between the primacord and wire is necessary in order to be sure that the wire is broken by the carbon and oxygen explosive rather than the primacord.

"Low-velocity impact resistance" indicates the resistance of the explosive composition to detonation by accidental impact and was determined in accordance with the procedures described in U. S. Bureau of Mines Bulletin 472, pages 20-27. The explosive composition of my invention has a low-velocity impact resistance of 1400 ft.-lbs. or more. In other words, this impact is required to accidentally detonate the composition.

"Burning in semi-confinement" indicates what may be expected if the explosive composition should be ignited after it has been loaded into the drill hole. A 1 1/4" diameter pipe was capped at both ends and provided in one cap with varying degrees of pressure relief by drilling various diameter holes. An explosive mixture contained in the pipe was then ignited with a slow burning fuse and success or failure to detonate was noted. The smaller the orifice necessary for the burning to cause an explosion, the safer the explosive.

"Oxygen absorption and retention."—The ability of the absorbent carbon to absorb and retain liquid oxygen was determined by immersing a 2 ounce sample of the carbon contained in a fire-resistant cotton bag in liquid oxygen. After ten minutes the bag and contents were removed and immediately weighed to determine the initial oxygen:carbon ratio. A timer was then started and the bag was left on the balance to determine the time required for evaporation to decrease the oxygen-carbon ratio to 2.0. The value obtained serves as an index of the retention times that can be expected in commercial blasting operations wherein the cartridges and filling methods employed result in longer retention times. A long retention time is desirable since it allows more time to prepare the explosive charges prior to their detonation.

Example No. 1

A sample of Williams coal, seam No. 6, which is a swelling, bituminous coal, having a volatile content of 39.8% by weight was milled to 70% —200 mesh. A tubular furnace of 30 inches inside diameter was pre-heated to a temperature of about 1000-1200° C. by burning gas in a burner placed in one end of the furnace. A stream of the coal was then fed into the furnace at a rate of 1200 lbs./hr. together with 1500 cu. ft./minute of air which was sufficient to reduce the volatile content of the coal down to about 4% by weight and burn a sufficient amount of the fixed carbon so that the yield of product collected in the cyclone was about 20% based upon the original coal. The product obtained had an ash content of 9.5%, a particle size of 73% —200 mesh, and a bulk density of 15.8 lbs./cu. ft. Oxidation absorption tests showed the initial oxygen:carbon ratio to be 3:1 and the oxygen retention time 11.7 minutes. Tests on liquid oxygen explosives prepared with this carbon showed the low-velocity impact resistance to be more than 1450 ft.-lbs. In semi-confinement tests, detonation failed to occur using an orifice of 1/4" in diameter. The detonation velocity of the explosive was found to be 15,600 ft./second.

Example No. 2

A sample of Ditney Hill coal was ground to 86% —200 mesh. This coal was also a swelling, bituminous coal and had a volatile content of 35.5%; ash content 4.6%. This coal was fed to a 4 inch tube furnace (pre-heated to 1100° C.) at a rate of 50 lbs./hr. with 40 cu. ft./minute of air. The product was cooled by water fogging prior to entry into the cyclone. A hard, granular absorbent carbon was obtained in a yield of 28% based

on the dry weight of the feed. This carbon had an ash content of 10.1%, a volatile content of 3.2%, a bulk density of 11.1 lbs./cu. ft., and a particle size of 85% —200 mesh. Oxygen absorption tests indicated that the carbon had the initial oxygen:carbon ratio of 4:1 and an oxygen retention time of 11.8 minutes. Tests made on liquid oxygen explosive prepared with this carbon showed the explosive to have a low-velocity impact resistance of more than 1200 ft.-lbs. Burning in semi-confinement tests failed to detonate the explosive using an orifice of 1/4" diameter. The detonation velocity of the explosive was 14,050 ft./second.

Example No. 3

For purposes of comparison a carbon prepared from wood bark and commonly used in liquid oxygen explosives after chemical treatment to make it fireproof was subjected to the aforesaid tests. Using a non-fireproofed sample, it was found to have a bulk density of 12.0 lbs./cu. ft., and an ash content of 1.9%. Oxygen absorption tests indicated that its initial oxygen:carbon ratio was 3.5 and oxygen retention time 12.0 minutes. A low-velocity impact test on a liquid oxygen explosive prepared with this carbon produced explosions at 930 ft.-lbs. In a semi-confinement test the explosive detonated when using an orifice of 1/4" diameter but not with an orifice of 5/8" diameter. The detonation velocity was 18,000 ft./second.

The explosives prepared according to my invention and described in Examples 1 and 2 were found to be highly effective and unusually safe despite the lack of any fire-proofing treatment of the absorbent carbon.

It is to be understood that the absorbent carbon employed in my invention may be classified (or milled and classified) by dry or wet methods in order to regulate the oxygen absorption characteristics. Also it is contemplated, when considered desirable, to activate the absorbent carbon product by means well known in the art, to increase its ability to absorb liquid oxygen.

It should also be understood that containers other than cloth bags may be used as cartridges in my method for producing the explosive. Such materials may be polyethylene, aluminum and other non-sparking metals.

Having thus described the nature of my invention, I

claim:

1. The method of producing a liquid oxygen explosive which comprises preparing a hard, granular, essentially non-activated absorbent carbon by the thermal expansion of finely divided bituminous coal suspended in an oxygen containing gas maintained at a temperature between about 1200° to 1700° C. and at an upheat rate higher than 1000° C./second (particle surface temperature), said carbon having the following properties: bulk density of 10-20 lbs./cu. ft., volatile content less than 5% by weight, ash content of about 8% to about 15% by weight, and particle size at least 70% less than 200 mesh; and thereafter causing liquid oxygen to be absorbed by the resulting absorbent carbon.

2. A process according to claim 1 in which the expansion zone is maintained at a temperature between 1350° to 1650° C.

3. A process according to claim 1 in which the coal has a volatile matter content of about 30 to 40% by weight.
